DRY-SEAL PRESSURE-TYPE GASHOLDERS
Frank Walter Horner, Jr., Park Ridge, Ill., assignor to
General American Transportation Corporation, Chi-
cago, Ill., a corporation of New York
Filed Feb. 16, 1962, Ser. No. 173,690
14 Claims. (Cl. 48—174)

The present invention relates to dry-seal pressure type gasholders, and more particularly to improved diaphragms for such gasholders.

A dry-seal pressure-type gasholder conventionally comprises a container including an upstanding substantially cylindrical shell or side wall, a substantially disk-shaped piston arranged in the container and movable in the vertical direction, an upstanding substantially cylindrical fender carried by the piston adjacent to the circumference thereof and spaced radially inwardly with respect to the shell to provide an annular space therebetween, and an annular curtain-like gas-impervious flexible diaphragm arranged in an upwardly directed annular loop in the annular space. In the arrangement, the diaphragm includes an annular outer wall sealed adjacent to the bottom thereof to an annular portion of the shell, an annular inner wall sealed adjacent to the bottom thereof to an annular portion of the piston, and an annular connecting wall extending between the top of the outer wall and the top of the inner wall, whereby the gas pressure in the container presses the outer wall into firm engagement with the inner surface of the shell and presses the inner wall into firm engagement with the outer surface of the fender. When the piston rises in the container, the material in the diaphragm is fed from the inner wall through the connecting wall into the outer wall; and conversely, when the piston falls in the container, the material in the diaphragm is fed from the outer wall through the connecting wall into the inner wall. Since the circumferential length of the inner surface of the shell is necessarily greater than the circumferential length of the outer surface of the fender, the outer wall of the diaphragm has a tendency to have a circumferential length that is greater than that of the inner wall of the diaphragm; with the result that folds, wrinkles and creases tend to form across the looped part of the diaphragm. This condition of the diaphragm is most objectionable as it leads to early puncture and mechanical failure of the diaphragm in the normal operating cycle of the piston.

In order to prevent such wrinkling of the material in the diaphragm as it is fed between the outer and inner walls thereof, many elaborate constructions of the diaphragm and of the associated fender have been employed heretofore, as disclosed in U.S. Patent No. 2,723,908, granted on November 15, 1955, to John H. Wiggins, John W. Allen and F. Walter Horner, and in U.S. Patent No. 2,756,132, granted on July 24, 1956, to John H. Wiggins. While these arrangements are reasonably satisfactory in the operation of the gasholder, they are entirely too expensive to manufacture and to maintain in service.

Accordingly, it is the general object of the present invention to provide in a gasholder of the type described, an improved and simplified diaphragm that is economical to manufacture and that requires no external devices or appliances to prevent wrinkling of the material therein incident to the feed of the material in the diaphragm between the outer and inner walls thereof.

Another object of the invention is to provide in a gasholder of the type described, an annular flexible diaphragm arranged in an upwardly directed annular loop in the annular space between the shell of the container and the fender carried by the piston arranged therein,

2

wherein the diaphragm has an unstrained circumferential length C_d that is less than the inner circumferential length C_s of the shell and that is greater than the outer circumferential length C_f of the fender, whereby the gas under pressure in the container produces circumferential tension strains in the material in the outer wall of the diaphragm so as to stretch the same to a circumferential length substantially equal to C_s without effecting wrinkling thereof and so as to press the thus stretched outer wall into firm engagement with the inner surface of the shell, and whereby the gas under pressure in the container produces circumferential compression strains in the material in the inner wall of the diaphragm so as to compress the same to a circumferential length substantially equal to C_f without effecting wrinkling thereof and so as to press the thus compressed inner wall into firm engagement with the outer surface of the fender, with the result that the vertical movement of the piston effects the feed of the material of the diaphragm between the outer wall and the inner wall through the connecting wall and the consequent reversal of the circumferential strains in the material thus fed.

A further object of the invention is to provide in a gasholder of the type described, a diaphragm of improved composite construction, whereby the same possesses as inherent characteristics thereof the previously described elastomeric qualities.

A still further object of the invention is to provide a diaphragm for a gasholder, wherein the diaphragm is of composite sandwich construction including an inner layer of material in contact with the gas stored in the container and an outer layer of material in contact with the atmosphere, wherein the materials of the two layers mentioned are especially selected for the special properties thereof that render them substantially ideally suited to the environmental operating conditions respectively encountered thereby, and wherein the materials of the two layers mentioned are so coordinated that the diaphragm as a whole possesses the previously described elastomeric qualities.

A further object of the invention is to provide a diaphragm of the type described that essentially comprises a gas-impervious inner layer and a resilient outer layer intimately bonded together, wherein the inner layer is formed of elastomeric organic material that is chemically inert to the gas stored in the container and that is characterized by substantial stretchability in the circumferential direction of the diaphragm, and wherein the outer layer is formed of elastomeric organic material that is resistant to atmospheric gases and to water vapor and that is characterized by both substantial stretchability and substantial compressibility in the circumferential direction of the diaphragm.

A further object of the invention is to provide a diaphragm of the type described that further comprises an intermediate layer of adhesive firmly securing together the inner and outer layers noted, wherein the intermediate layer is formed of organic material that is characterized by substantial flexibility after setting thereof.

Yet another object of the invention is to provide a diaphragm of the type described, wherein each of the layers noted essentially comprises an elastomeric material that is in the form of a synthetic rubber or a synthetic organic resin having the general properties of a synthetic rubber.

A further object of the invention is to provide in a gasholder, a diaphragm of the type described that incorporates a textile fabric that is elastic and that is characterized by exceedingly great tensile strength in the radial direction between the outer and inner perimeters thereof that are respectively sealed to the shell and to the piston in the gasholder.

A still further object of the invention is to provide a gas-

holder of the character described that is of the multi-piston type including a number of nested pistons movable in the vertical direction and also including a corresponding number of flexible diaphragms of the type specified.

Further features of the invention pertain to the particular arrangement of the elements of the gasholder and of the diaphragm incorporated therein, whereby the above-outlined and additional operating features thereof are attained.

The invention, both as it is organization and method of operation, together with further objects and advantages thereof, will best be understood by reference to the following specification, taken in connection with the accompanying drawings, in which:

FIGURE 1 is a fragmentary plan view, partly in horizontal section, of a dry-seal pressure-type gasholder incorporating a diaphragm embodying the present invention;

FIG. 2 is a fragmentary vertical sectional view of the gasholder, this view being taken in the direction of the arrows along the line 2—2 in FIG. 1;

FIG. 3 is a fragmentary vertical sectional view, similar to FIG. 2, of a modified form of the gasholder that is provided with the two nested pistons and incorporating two corresponding diaphragms embodying the present invention.

FIG. 4 is a greatly enlarged sectional view of one of the diaphragms incorporated in the gasholders of FIGS. 1 to 3, inclusive;

FIG. 5 is a greatly enlarged sectional view, similar to FIG. 4, of a modified form of the diaphragm; and

FIG. 6 is a greatly enlarged sectional view, similar to FIG. 4, of another modified form of the diaphragm.

Referring now to FIGS. 1 and 2 of the drawings, the gasholder 10 there illustrated and embodying the features of the present invention comprises a container 11 that includes an upstanding substantially cylindrical outer wall or shell 12, a substantially disk-shaped bottom wall or floor 13 and a substantially cone-shaped top wall or roof 14; which container 11 is adapted to contain and to store under pressure such gases as natural gas, light petroleum gases, coke oven gas, etc. The stored gases have a wide variety of compositions; for instance, coke oven gas essentially comprises methane, hydrogen, carbon dioxide, carbon monoxide, hydrogen sulfide, oxygen, nitrogen and aromatic compounds including benzene, toluene and pyridine, and adulterant compounds such as carbon disulfide and mercaptan sulphur. Also, the gasholder 10 comprises a substantially disk-shaped piston 15 arranged in the container 11 and movable in the vertical direction; which piston 15 carries adjacent to the circumference thereof an upstanding substantially cylindrical fender 16 that is spaced radially inwardly with respect to the shell 12 to provide an annular space 17 therebetween.

An annular curtain-like gas-impervious flexible diaphragm 20 is arranged in an upwardly directed annular loop in the annular space 17; and the diaphragm 20 essentially comprises an annular outer wall 21 and an annular inner wall 22 and an annular connecting wall 23. The bottom of the outer wall 21 is sealed to an annular portion of the shell 12 by an associated annular sealing bar 31; and the bottom of the inner wall 22 is suitably sealed to an annular portion of the piston 15 adjacent to the bottom of the fender 16. The top of the outer wall 21 integrally joins the outer looped portion of the connecting wall 23; and the top of the inner wall 22 integrally joins the inner looped portion of the connecting wall 23. The gas contained in the gasholder 10 is stored under pressure in the lower portion of the container 11 below the piston 15 and the diaphragm 20; whereby the lower or inner side of the diaphragm 20 is in contact with the stored gas. The upper portion of the container 11 above the piston 15 and the diaphragm 20 is vented to the atmosphere, usually through a series of vent devices, not shown;

whereby the upper or outer side of the diaphragm 20 is in contact with the atmosphere.

When the container 11 is empty of stored gas, the piston 15 occupies its lower portion, as illustrated in full lines in FIG. 2; when the container 11 is full of stored gas, the piston 15 occupies its upper position, as illustrated in broken lines in FIG. 2; and when the container 11 is partially full of stored gas, the piston 15 occupies an appropriate intermediate position with respect to its lower and upper positions noted. The piston 15 in its lower position is supported on the floor 13; and the piston 15 in its upper position is disposed near the roof 14, the upper position of the piston 15 being established by a volume control safety vent, not shown. In the operation of the piston 15 in the vertical direction between its lower and upper positions, a substantially constant pressure is maintained upon the stored gas in the container 11; which pressure of the stored gas is normally held or maintained at about 20" water gauge. Also the gas under pressure stored in the container 11 forces the diaphragm 20 into its upwardly directed annular loop-like configuration, so as to press the outer wall 21 of the diaphragm 20 into firm engagement with the adjacent portion of the inner surface of the shell 11 and so as to press the inner wall 22 of the diaphragm 20 into firm engagement with the adjacent portion of the outer surface of the fender 16. As the piston 15 falls in the container 11, the material in the outer wall 21 of the diaphragm 20 is fed-off of the inner surface of the shell 12 through the connecting wall 23 into the inner wall 22 and is thus pressed into firm engagement with the outer surface of the fender 16. Conversely, as the piston 15 rises in the container 11, the material in the inner wall 22 of the diaphragm 20 is fed-off of the outer surface of the fender 16 through the connected wall 23 into the inner wall 21 and is thus pressed into firm engagement with the inner surface of the shell 12.

In the gasholder 10, the shell 12 has an inner radius R_s , as illustrated in FIG. 2, and a corresponding inner circumferential length C_s . Similarly, the fender 16 has an outer radius R_f , as illustrated in FIG. 2, and a corresponding outer circumferential length C_f . The diaphragm 20 has an unstrained radius R_d , as illustrated in FIG. 2, and a corresponding unstrained circumferential length C_d . In the arrangement, the relationship exists:

$$C_s > C_d > C_f$$

The diaphragm 20 is formed of elastomeric material that is both stretchable and compressible circumferentially with respect to the circumferentially unstrained condition thereof. It must be realized that initially such material has definite characteristics of stretchability and compressibility, but that the recovery from the stretched condition when such condition is maintained for any length of time, becomes lessened. Thus it is important to have the quality of compressibility to maintain the seal in unwrinkled condition when the gas under pressure in the container 11 produces circumferential tension and compression strains in the material in the walls of the diaphragm 20 as the vertical movement of the piston 15 effects the feed of the material of the diaphragm 20 between the outer wall 21 and the inner wall 22 thereof through the connecting wall 23 thereof and the consequent reversal of the circumferential strains in the material of the diaphragm 20 thus fed.

In a very small gasholder 10 of about 50 cu. ft. C_s is equal to about 104% of C_f , whereas in a relatively large gasholder 10 of about 5,000,000 cu. ft. C_s is equal to about 101 1/4% of C_f . The unstrained circumferential length C_d of the diaphragm 20 is equal to about $1/2 (C_s + C_f)$; whereby the material of the diaphragm 20 is stretched circumferentially by about 0.6% to about 2% of C_d and is compressed circumferentially by the same percentages all without inducing wrinkles across the looped portion of the diaphragm 20.

In constructing the gasholder 10, the diaphragm 20 is fabricated from a plurality of straight runs of material into a composite ring having a total internal circumferential length and a total external circumferential length of approximately C_d in unstrained condition of the material. The thus fabricated diaphragm 20 has an inner side and an outer side that are different from each other, as explained more fully hereinafter; whereby the composite diaphragm 20 is then placed in the annular space 17 between the shell 12 and the fender 16 and with the inner side in downward position so that ultimately it will be in contact with the gas stored in the container 11. The bottom of the outer wall 21 of the diaphragm 20 is suitably stretched to the circumferential length C_s and is suitably secured to the shell 12 appropriately above the floor 13, utilizing the sealing bar 31. The bottom of the inner wall 22 of the diaphragm 20 is then suitably compressed to the circumferential length C_f without inducing wrinkles across the looped portion of the diaphragm 20 and is suitably secured to the piston 15 adjacent to the bottom of the fender 16. Accordingly, at this time, the bottom of the inner wall 22 is compressed with respect to the unstrained circumferential length C_d thereof and into the circumferential length C_f , while the bottom of the outer wall 21 is stretched with respect to the unstrained circumferential length C_d thereof and into the circumferential length C_s , without inducing wrinkles in the diaphragm 20. Subsequently, when the gas to be stored in the container 11 is introduced thereto below the piston 15 and the diaphragm 20, the diaphragm 20 is blown into its normally upwardly directed annular loop-like configuration, as shown in FIG. 2. At this time, the remainder of the outer wall 21 of the diaphragm 20 is stretched to the circumferential length C_s and is pressed into firm engagement with the inner surface of the shell 12, and the remainder of the inner wall 22 of the diaphragm 20 is compressed to the circumferential length C_f and is pressed into firm engagement with the outer surface of the fender 16, all without inducing wrinkles in the diaphragm 20.

Referring now to FIG. 3, the modified form of the gasholder 110 there illustrated is basically the same as the gasholder 10, as described above in conjunction with FIGS. 1 and 2, except that in this case, the piston is of composite construction including two piston sections 115A and 115B arranged in nested relation. More particularly, the outer piston section 115A is spaced radially inwardly with respect to the shell 112 of the container 111 and the inner piston section 115B is spaced radially inwardly with respect to the outer piston section 115A. The outer piston section 115A carries an upstanding substantially cylindrical fender 116A, and the inner piston section 115B carries an upstanding substantially cylindrical fender 116B. Also, the diaphragm is of composite construction including two diaphragm sections 120A and 120B arranged in nested relation. Specifically, the outer diaphragm section 120A is arranged between the inner surface of the shell 112 of the container 111 and the outer surface of the outer fender 116A; while the inner diaphragm section 120B is arranged between the inner surface of the outer fender 116A and the outer surface of the inner fender 116B. Accordingly, the outer diaphragm section 120A includes an annular outer wall 121A that is sealed adjacent to the bottom thereof to an annular portion of the shell 112, an annular inner wall 122A that is sealed adjacent to the bottom thereof to an annular portion of the outer piston 115A, and an annular connecting wall 123A extending between the top of the outer wall 121A and the top of the inner wall 122A. Likewise, the inner diaphragm section 120B includes an annular outer wall 121B that is sealed adjacent to the bottom thereof to an annular portion of the outer piston 115A, an annular inner wall 122B that is sealed adjacent to the bottom thereof to an annular portion of the inner piston 115B,

and an annular connecting wall 123B extending between the top of the outer wall 121B and the top of the inner wall 122B.

The inner piston 115B has a lower position, illustrated in full lines in FIG. 3, wherein it is supported upon the floor 113 of the container 111; and the outer piston 115A has a lower position illustrated in full lines in FIG. 3, wherein it is supported upon associated structure 134 carried jointly by the floor 113 and by the shell 112 of the container 111. Also the inner piston 115B has an upper position shown in broken lines in FIG. 3, wherein it is disposed entirely within the upper portion of the outer piston 115A; and the outer piston 115A has an upper position shown in broken lines in FIG. 3, wherein it is disposed adjacent to the roof 114 of the container 111 as established by the volume control safety valve, not shown.

In the operation of the gasholder 110, when the gas to be stored is first admitted into the container 111 below the piston sections 115A and 115B and below the diaphragm sections 120A and 120B, the inner piston section 115B first rises within the outer piston section 115A and into its upper position, as shown in broken lines in the middle of FIG. 3. At this time, further upward movement of the inner piston section 115B relative to the outer piston section 115A is arrested by the engagement of the top of the inner fender 116B with the top of the outer fender 116A, whereby the two piston sections 115A and 115B move further upwardly as a unit incident to the introduction of additional gas into the lower portion of the container 111. When the lower portion of the container 111 is completely full of the gas to be stored, the outer piston section 115A is moved into its upper position carrying the inner piston section 115B therewith and into the positions as shown in broken lines at the top of FIG. 3.

In the gasholder 110, the shell 112 has an inner radius of R_s and a corresponding inner circumferential length of C_s ; the outer fender 116A has an outer radius of R_{1fo} and a corresponding outer circumferential length of C_{1fo} ; the outer fender 116A has an inner radius of R_{1fi} and a corresponding inner circumferential length of C_{1fi} ; the inner fender 116B has an outer radius of R_{2fo} and a corresponding outer circumferential length of C_{2fo} ; the outer diaphragm section 120A has an unstrained radius R_{1d} and a corresponding unstrained circumferential length C_{1d} ; and the inner diaphragm section 120B has an unstrained radius R_{2d} and a corresponding unstrained circumferential length C_{2d} . In the gasholder 110, C_s is equal to about 101% to about 104% of C_{1fo} , and C_{1fi} is equal to about 101% to about 104% of C_{2fo} . C_{1d} is equal to about $\frac{1}{2}(C_s + C_{1fo})$ and C_{2d} is equal to about $\frac{1}{2}(C_{1fi} + C_{2fo})$.

The mode of constructing the gasholder 110 is substantially the same as that employed in constructing the gasholder 10 as previously described. Specifically, the bottom of the outer wall 121A of the outer diaphragm section 120A is stretched circumferentially from about 0.6% to about 2% of the unstrained circumferential length C_{1d} and is sealed to the adjacent annular portion of the shell 112; and similarly, the bottom of the inner wall 122A of the outer diaphragm section 120A is compressed circumferentially by about 0.6% to about 2% of the unstrained circumferential length C_{1d} thereof, without inducing wrinkles across the loop of the material and is sealed to the adjacent annular portion of the outer piston section 115A. Specifically, the bottom of the outer wall 121B of the inner diaphragm section 120B is stretched circumferentially by about 0.6% to about 2% of the unstrained circumferential length C_{2d} thereof and is sealed to the adjacent annular portion of the outer piston 115A; and similarly, the bottom of the inner wall 122B of the inner diaphragm section 120B is compressed circumferentially by about 0.6% to about 2% of the unstrained circumferential length C_{2d} thereof, without inducing wrinkles across the loop of the material and is sealed

to the adjacent annular portion of the inner piston section 115B.

Referring now to FIG. 4, there is shown a cross section of a body of diaphragm material 420 that is particularly suitable for the fabrication of the diaphragm 20 in the gas holder 10 of FIGS. 1 and 2, and for the fabrication of the diaphragm sections 120A and 120B in the gas-holder 110 of FIG. 3; which body of diaphragm material 420 is of composite sandwich construction including a gas-impervious inner layer 425 and a resilient outer layer 426 intimately bonded together by an intermediate layer of adhesive 427. The inner layer 425 is formed of a sheet of elastomeric organic material that is chemically inert to the gas that is stored in the container of the gas-holder and that is characterized by substantial stretchability in the circumferential direction of the ultimately fabricated diaphragm; the outer layer 426 is formed of a body of elastomeric organic material of cellular structure that is resistant to atmospheric gases and to water vapor and that is characterized by both substantial stretchability and substantial compressibility in the circumferential direction of the ultimately fabricated diaphragm; and the intermediate layer 427 is formed of a film of any suitable adhesive material that is characterized by substantial elasticity and flexibility after setting thereof. More particularly, the inner layer 425 essentially comprises a textile-reinforcing fabric 425a that is suitably embedded in a body 425b of synthetic rubber or synthetic organic resin having the general properties of rubber; while the outer layer 426 essentially comprises a cushion or mattress of foamed synthetic rubber or synthetic organic resin having the general properties of foamed rubber; and the intermediate layer essentially comprises a synthetic rubber adhesive or a synthetic organic resin adhesive having the general properties of a rubber adhesive. Preferably, the textile fabric 425a comprises cords that extend between the inner and outer perimeters of the ultimately fabricated diaphragm and that lend great tensile strength thereto that is in the general range 180# to 600# per inch of circumferential length of the ultimately fabricated diaphragm; which cords may be formed of nylon, rayon, etc., in the usual manner of the cords incorporated in the textile fabrics normally utilized in the production of heavy-duty tires for trucks, road-working machines, etc.

In a constructional example of the diaphragm material 420, the inner layer 425 has a thickness in the general range 0.010" to 0.060", the outer layer 426 has thickness in the general range $\frac{1}{4}$ " to $\frac{1}{2}$ ", and the intermediate layer 427 has a thickness in the general range one to several mils; whereby the composite diaphragm material 420 is elastomeric and is stretchable in the circumferential direction of the ultimately fabricated diaphragm by at least 10% of the unstrained circumferential length thereof and is compressible in the circumferential direction when put in the loop form of the ultimately fabricated diaphragm by at least 4% of the unstrained circumferential length thereof without inducing wrinkles therein.

In the diaphragm material 420, the inner layer 425 constitutes a primary membrane having a low permeability to the gas stored in the container, the intermediate layer 427 constitutes a flexible bonding agent that may also have a low permeability to the gas stored in the container and also to atmospheric gases and to water vapor, and the outer layer 426 serves fundamentally as a cushion or mattress, so that this foamed material may be of either the open-cell type or the closed-cell type, depending upon the particular constituents thereof. More particularly, the intermediate adhesive layer 427 retains substantial plasticity, after setting thereof. Since the outer layer 426 is resilient, it is capable of readily peeling off from the adjacent inner surface of the associated shell and upon the adjacent outer surface of the associated fender and back again in the normal operation of the ultimately fabricated diaphragm, as previously explained.

In the diaphragm material 420, the outer layer 426

contributes sufficient body and mass thereto that short sections of the diaphragm material 420 possess sufficient rigidity or stiffness to be self-supporting; although longer sections of the diaphragm material 420 are altogether flexible and pliable, as described above. These characteristics of the elastomeric diaphragm material 420 clearly distinguish it from the altogether limp diaphragm materials that have been employed heretofore in the fabricating of diaphragms for gasholders of the present type.

Satisfactory constructional components for the several layers of the diaphragm material 420 are as follows:

The inner layer 425 is formed of textile fabric reinforced nitrile rubber, polysulfide rubber, polychloroprene, "Chemigum SL," "Ensolite," or polyurethane resin; the outer layer 426 is formed of foamed nitrile rubber, polysulfide rubber, chloroprene, "Chemigum SL," "Ensolite" or polyurethane resin; and the intermediate adhesive layer 427 is formed of "Hycar" rubber cement, "Pliobond" rubber cement, "Chemigum SL" resin cement or polyurethane resin cement.

A particularly advantageous construction of the diaphragm material 420 comprises the inner layer 425 formed of textile fabric reinforced nitrile rubber, the outer layer 426 formed of foamed polyurethane and the intermediate adhesive layer 427 formed of "Hycar" rubber cement.

Referring now to FIG. 5, the modified form of the diaphragm material 520 there illustrated is fundamentally of the same construction as that of the diaphragm material 420 as described in conjunction with FIG. 4; which diaphragm material 520 comprises the gas-impervious inner layer 525 and the resilient outer layer 526 intimately bonded together by the intermediate layer of adhesive 527. In this case, the inner layer 525 comprises a simple sheet of elastomeric organic material that is chemically inert to the gas that is stored in the container of the gas-holder and that is characterized by substantial stretchability in the circumferential direction of the ultimately fabricated diaphragm, whereby the inner layer 525 constitutes a primary membrane having a low permeability to the gas stored in the container. Specifically, the inner layer 525 may be formed of a sheet of nitrile rubber, polysulfide rubber, polychloroprene, "Chemigum SL," "Ensolite," "Mylar" or polyurethane resin, whereas the outer layer 526 and the intermediate layer 527 may be formed of the materials as previously explained in conjunction with the corresponding layers 426 and 427.

In a constructional example of the diaphragm material 520, the inner layer 525 has a thickness in the general range 0.010" to 0.060" and is preferably formed of "Mylar," the outer layer 526 has a thickness in the general range $\frac{1}{4}$ " to $\frac{1}{2}$ " and is preferably formed of foamed polyurethane resin, and the intermediate layer 527 has a thickness in the general range one to several mils and is preferably formed of "Hycar" rubber cement; whereby the composite diaphragm material 520 is elastomeric and is stretchable in the circumferential direction of the ultimately fabricated diaphragm by at least 10% of the unstrained circumferential length thereof and is compressible in the circumferential direction when put in the loop form of the ultimately fabricated diaphragm by at least 4% of the unstrained circumferential length thereof without inducing wrinkles therein.

Referring now to FIG. 6, the modified form of the diaphragm material 620 there illustrated comprises a combination of the constructions of the diaphragm materials 420 and 520 as described in conjunction with FIGS. 4 and 5; which diaphragm material 620 comprises the gas-impervious inner layer 625, the resilient outer layer 626, the gas-impervious intermediate layer 627, the intermediate layer of adhesive 627a bonding together the layers 625 and 627, and the intermediate layer of adhesive 627b bonding together the layers 626 and 627. In this case, the inner layer 625 comprises a simple sheet of elastomeric organic material corresponding to the inner layer 525, the

outer layer 626 comprises a resilient cushion or mattress material corresponding to the outer layer 426, the intermediate layer 627 comprises a textile fabric reinforced sheet corresponding to the inner layer 425, whereas the intermediate layers 627a and 627b may be formed of the materials as previously explained in conjunction with the corresponding intermediate layers 427 and 527.

In a constructional example of the diaphragm material 620, the inner layer 625 has a thickness in the general range 0.005" to 0.030" and is preferably formed of "Mylar," the intermediate layer 627 has a thickness in the general range 0.005" to 0.030" and is preferably formed of textile fabric reinforced nitrile rubber, the outer layer 626 has a thickness in the general range 1/4" to 1/2" and is preferably formed of foamed polyurethane resin, and each of the intermediate layers 627a and 627b has a thickness in the general range one to several mils and is preferably formed of "Hycar" rubber cement; whereby the composite diaphragm material 620 is elastomeric and is stretchable in the circumferential direction of the ultimately fabricated diaphragm by at least 10% of the unstrained circumferential length thereof and is compressible in the circumferential direction when put in the loop form of the ultimately fabricated diaphragm by at least 4% of the unstrained circumferential length thereof without inducing wrinkles therein.

Consider now the chemical definitions of the foregoing named compositions.

Nitrile rubber (GR-A) essentially comprises copolymers of butadiene and acrylonitrile and has the generalized formula:

Polysulfide rubber has the generalized formula:

Polychloroprene (GR-M) has the generalized formula:

"Chemigum SL" comprises a polyester of ethylene glycol and propylene glycol and adipic acid (to produce a linear polymer) that has been reacted with a diisocyanate (to produce urethane cross linkages).

"Ensolite" comprises a nitrile rubber (copolymers of butadiene and acrylonitrile) modified by a content of about 25% by weight of polyvinyl chloride resin.

"Mylar" comprises a polyester of ethylene glycol and terephthalic acid.

A typical polyurethane comprises polymers produced by the addition reaction between a polyisocyanate and a hydroxyl-rich compound (at least 2 hydroxyl groups per molecule), such as glycols, polyesters, polyethers, etc.

"Hycar" rubber cement comprises a nitrile rubber (copolymers of butadiene and acrylonitrile) modified by a content of a few percent by weight of phenolic resin, as well as a plasticizer (normally diethylphthalate).

"Pliobond" rubber cement comprises a nitrile rubber (copolymers of butadiene and acrylonitrile) modified by a few percent by weight of a reinforcing resin (such as polyvinyl chloride) and a suitable plasticizer.

"Chemigum SL" resin cement comprises "Chemigum SL" resin modified by a few percent by weight of a reinforcing resin and a suitable plasticizer.

Polyurethane resin cement comprises polyurethane resin modified by a few percent by weight of a reinforcing resin and a suitable plasticizer.

The foregoing compositions are vastly superior to natural rubber with respect to resistance to swelling and to deterioration in the presence of petroleum products, with respect to chemical inertness in the presence of a wide variety of gases that may be stored in the container of the gasholder, with respect to resistance to atmospheric gases, water vapor, ozone and aging, and with respect to

5 a low permeability to a wide variety of gases that may be stored in the container of the gasholder and to atmospheric gases and to water vapor; whereby the diaphragm materials 420, 520 and 620 have an exceedingly long useful life in the ultimately fabricated diaphragms of the gasholders.

In the diaphragm constructions 420, 520 and 620, as respectively shown in FIGS. 4 to 6, inclusive, the inner and outer layers of material are separate and distinct with 10 respect to each other, either being chemically identical or totally dissimilar, and bonded together by a separate and distinct intermediate layer. However, it should be readily understood that a suitable diaphragm of the character described may also be constructed by foaming the 15 rubber or other plastic material directly onto the inner gas-impermeable film or fabric layer, thus obviating any distinct intermediate layer of bonding material. Also, it is possible to form a surface on a body of foamed rubber or plastic material that is inert and impermeable to gas to 20 be stored, by sealing such surface, employing either a heat treatment or a chemical treatment.

In view of the foregoing, it is apparent that there has been provided in a dry-seal pressure-type gasholder, an improved diaphragm of composite construction that is capable of feeding in either direction between the inner surface of the shell of the container and the outer surface of the fender carried by the piston, without inducing wrinkles, folds or creases therein, whereby the diaphragm has an exceedingly long useful life in the gasholder. Furthermore, the composite diaphragm is fabricated of a plurality of layers of component materials that are especially selected to impart to the diaphragm the required elastomeric properties, to resist chemical attack by a wide variety of gases stored in the gasholder, to resist oxidation and aging in the presence of such stored gases, atmospheric gases and water vapor and to provide a composite diaphragm that has an exceedingly low permeability to the stored gases and to atmospheric gases and to water vapor.

40 While there has been described what is at present considered to be the preferred embodiment of the invention, it will be understood that various modifications may be made therein, and it is intended to cover in the appended claims all such modifications as fall within the true spirit and scope of the invention.

45 What is claimed is:

1. In a dry-seal pressure-type gasholder, a container including an upstanding substantially cylindrical shell, a substantially disk-shaped piston arranged in said container and movable in the vertical direction, an upstanding substantially cylindrical fender carried by said piston adjacent to the circumference thereof and spaced radially inwardly with respect to said shell to provide an annular space therebetween, and an annular curtain-like gas-impermeable flexible diaphragm arranged in an upwardly directed annular loop in said annular space, said diaphragm including an annular outer wall sealed adjacent to the bottom thereof to an annular portion of said shell and an annular inner wall sealed adjacent to the bottom thereof to an annular portion of said piston and an annular connecting wall extending between the top of said outer wall and the top of said inner wall, said diaphragm being formed of elastomeric material and having a thickness of at least about 1/4", the circumferential length of said diaphragm being both stretchable and compressible by about 0.6% to about 2% of the unstrained circumferential length thereof without inducing wrinkles in the material therein, said shell having an inner circumferential length C_s , said diaphragm having an unstrained circumferential length C_d , said fender having an outer circumferential length C_f , wherein $C_s > C_d > C_f$, the material in said outer wall being constantly stretched and the material in said inner wall being constantly compressed when said diaphragm is put in place, the gas under pressure in said container producing constant circumferential strains

in the material in said diaphragm so as to stretch the material in said outer wall into firm engagement with the inner surface of said shell and to compress the material in said inner wall into firm engagement with the outer surface of said fender, whereby vertical movement of said piston effects the feed of the material in said diaphragm between said outer wall and said inner wall through said connecting wall and the consequent reversal of the circumferential strains in the material thus fed, all without inducing wrinkles in said diaphragm.

2. The gasholder set forth in claim 1, wherein C_s is equal to about 101% to about 104% of C_f , and C_d is equal to about $\frac{1}{2}(C_s+C_f)$.

3. In a dry-seal pressure-type gasholder, a container including an upstanding substantially cylindrical shell, a first substantially annular piston arranged in said container and movable in the vertical direction, a first upstanding substantially cylindrical fender carried by said first piston and spaced radially inwardly with respect to said shell to provide a first annular space therebetween, a first annular curtain-like gas-impervious flexible diaphragm arranged in an upwardly directed annular loop in said first annular space, said first diaphragm including a first annular outer wall sealed adjacent to the bottom thereof to an annular portion of said shell and a first annular inner wall sealed adjacent to the bottom thereof to an annular portion of said first piston and a first annular connecting wall extending between the top of said first outer wall and top of said first inner wall, a second substantially disk-shaped piston arranged in said container and movable in the vertical direction, a second upstanding substantially cylindrical fender carried by said second piston and spaced radially inwardly with respect to said first fender to provide a second annular space therebetween, and a second annular curtain-like gas-impervious flexible diaphragm arranged in an upwardly directed annular loop in said second annular space, said second diaphragm including a second annular outer wall sealed adjacent to the bottom thereof to an annular portion of said second piston and a second annular inner wall sealed adjacent to the bottom thereof to an annular portion of said second piston and a second annular connecting wall extending between the top of said second outer wall and the top of said second inner wall, each of said diaphragms being formed of elastomeric material and having a thickness of at least about $\frac{1}{4}$ ", the circumferential length of each of said diaphragms being both stretchable and compressible by about 0.6% to about 2% of the unstrained circumferential length thereof without inducing wrinkles in the material therein, said shell having an inner circumferential length C_s , said first diaphragm having an unstrained circumferential length C_d , said first fender having an outer circumferential length C_f and an inner circumferential length C_{fi} , said second diaphragm having an unstrained circumferential length C_d , said second fender having an outer circumferential length C_{fo} , wherein

$$C_s > C_d > C_f > C_{fi} > C_d > C_{fo}$$

the material in said first outer wall being constantly stretched and the material in said first inner wall being constantly compressed when said first diaphragm is put in place, the gas under pressure in said container producing constant circumferential strains in the material in said first diaphragm so as to stretch the material in said first outer wall into firm engagement with the inner surface of said shell and to compress the material in said first inner wall into firm engagement with the outer surface of said first fender, whereby vertical movement of said first piston effects the feed of the material in said first diaphragm between said first outer wall and said first inner wall through said first connecting wall and the consequent reversal of the circumferential strains in the material thus fed, all without inducing wrinkles in said first diaphragm, the material in said second outer wall being constantly stretched and the material in said second inner wall being

constantly compressed when said second diaphragm is put in place, the gas under pressure in said container producing constant circumferential strains in the material in said second diaphragm so as to stretch the material in said second outer wall into firm engagement with the inner surface of said first fender and to compress the material in said second inner wall into firm engagement with the outer surface of said second fender, whereby vertical movement of said second piston effects the feed of the material in said second diaphragm between said second outer wall and said second inner wall through said second connecting wall and the consequent reversal of the circumferential strains in the material thus fed, all without inducing wrinkles in said second diaphragm.

4. The gasholder set forth in claim 3, wherein C_s is equal to about 101% to about 104% of C_{fo} , C_d is equal to about $\frac{1}{2}(C_s+C_{fo})$, C_{fi} is equal to about 101% to about 104% of C_{fo} , and C_d is equal to about $\frac{1}{2}(C_{fi}+C_{fo})$.

5. In a dry-seal pressure-type gasholder, a container including an upstanding substantially cylindrical shell, a substantially cylindrical piston arranged in said container and movable in the vertical direction, said piston being spaced radially inwardly with respect to said shell to provide an annular space therebetween, and an annular curtain-like gas-impervious flexible diaphragm arranged in an upwardly directed annular loop in said annular space, said diaphragm including an annular outer wall sealed adjacent to the bottom thereof to an annular portion of said shell and an annular inner wall sealed adjacent to the bottom thereof to an annular portion of said piston and an annular connecting wall extending between the top of said outer wall and the top of said inner wall, whereby vertical movement of said piston in said shell effects the feed of the material in said diaphragm between said outer and inner walls via said connecting wall and the consequent reversal of the circumferential strains in the material thus fed, said diaphragm being formed of elastomeric material and having a thickness of at least about $\frac{1}{4}$ ", the circumferential length of said diaphragm being both stretchable and compressible by about 0.6% to about 2% of the unstrained circumferential length thereof without inducing wrinkles in the material therein.

6. In a dry-seal pressure-type gasholder including a substantially cylindrical container and a substantially cylindrical piston axially movably arranged in said container, said piston being spaced radially inwardly with respect to said container to provide an annular space therebetween, a substantially ring-like flexible diaphragm arranged in said annular space and sealed adjacent to the outer perimeter thereof to said container and sealed adjacent to the inner perimeter thereof to said piston, wherein said diaphragm has an inner side in contact with the gas in said container and an outer side in contact with the atmosphere, whereby axial movement of said piston in said container effects the feed of the material in said diaphragm between the outer portion thereof disposed adjacent to said container and the inner portion thereof disposed adjacent to said piston and the consequent reversal of the circumferential strains in the material thus fed; said diaphragm being of composite construction including a gas-impervious inner layer and a resilient outer layer intimately bonded together, said inner layer being relatively thin and formed of elastomeric organic material that is chemically inert to the gas stored in said container and that is characterized by substantial stretchability in the circumferential direction of said diaphragm, said outer layer being relatively thick and formed of elastomeric organic material that is resistant to atmospheric gases and to water vapor and that is characterized by both substantial stretchability and substantial compressibility in the circumferential direction of said diaphragm, said composite diaphragm having a thickness of at least about $\frac{1}{4}$ ", the circumferential length of said composite diaphragm being both stretchable and compressible by about 0.6%

to about 2% of the unstrained circumferential length thereof without inducing wrinkles in the material therein.

7. The gasholder set forth in claim 6, wherein said composite diaphragm has a tensile strength between the inner and outer perimeters thereof in the range 180 pounds to 600 pounds per inch of circumferential length thereof.

8. The gasholder set forth in claim 6, wherein said inner layer has a thickness in the range 0.010" to 0.060" and said outer layer has a thickness in the range $\frac{1}{4}$ " to $\frac{1}{2}$ ".

9. The gasholder set forth in claim 6, wherein said outer layer essentially comprises a closed-cell synthetic organic resin.

10. The gasholder set forth in claim 6, wherein said outer layer essentially comprises an open-cell synthetic organic resin.

11. In a dry-seal pressure-type gasholder including a substantially cylindrical container and a substantially cylindrical piston axially movably arranged in said container, said piston being spaced radially inwardly with respect to said container to provide an annular space therebetween, a substantially ring-like flexible diaphragm arranged in said annular space and sealed adjacent to the outer perimeter thereof to said container and sealed adjacent to the inner perimeter thereof to said piston, wherein said diaphragm has an inner side in contact with the gas in said container and an outer side in contact with the atmosphere, whereby axial movement of said piston in said container effects the feed of the material in said diaphragm between the outer portion thereof disposed adjacent to said container and the inner portion thereof disposed adjacent to said piston and the consequent reversal of the circumferential strains in the material thus fed; said diaphragm being of composite sandwich construction including a gas-impervious inner layer, a resilient outer layer, and an intermediate layer of adhesive firmly securing together said inner and outer layers, said inner layer being relatively thin and formed of elastomeric organic material that is chemically inert to the gas stored in said container and that is characterized by substantial stretchability in the circumferential direction of said diaphragm, said outer layer being relatively thick and formed of elastomeric organic material that is resistant to atmospheric gases and to water vapor and that is characterized by both substantial stretchability and substantial compressibility in the circumferential direction of said diaphragm, said intermediate layer being relatively thin and formed of organic material that is characterized by substantial elasticity and flexibility after setting thereof, said composite diaphragm having a thickness of at least about $\frac{1}{4}$ ", the circumferential length of said composite diaphragm being both stretchable and compressible by about 0.6% to about 2% of the unstrained circumferential length thereof without inducing wrinkles in the material therein.

12. In a dry-seal pressure-type gasholder including a substantially cylindrical container and a substantially cylindrical piston axially movably arranged in said container, said piston being spaced radially inwardly with respect to said container to provide an annular space therebetween, a substantially ring-like flexible diaphragm arranged in said annular space and sealed adjacent to the outer perimeter thereof to said container and sealed adjacent to the inner perimeter thereof to said piston, wherein said diaphragm has an inner side in contact with the gas in said container and an outer side in contact with the atmosphere, whereby axial movement of said piston in said container effects the feed of the material in said diaphragm between the outer portion thereof disposed adjacent to said container and the inner portion thereof disposed adjacent to said piston and the consequent reversal of the circumferential strains of the material thus fed; said diaphragm being of composite construction including a gas-impervious inner layer and a resilient outer layer intimately bonded together, said inner layer being formed of a relatively thin sheet of elastomeric synthetic organic resin

that is chemically inert to the gas stored in said container and that is characterized by substantial stretchability in the circumferential direction of said diaphragm, said outer layer being formed of a relatively thick mattress of foamed elastomeric synthetic organic material that is resistant to atmospheric gases and to water vapor and that is characterized by both substantial stretchability and substantial compressibility in the circumferential direction of said diaphragm, said composite diaphragm having a thickness of at least about $\frac{1}{4}$ ", the circumferential length of said composite diaphragm being both stretchable and compressible by about 0.6% to about 2% of the unstrained circumferential length thereof without inducing wrinkles in the material therein.

13. In a dry-seal pressure-type gasholder including a substantially cylindrical container and a substantially cylindrical piston axially movably arranged in said container, said piston being spaced radially inwardly with respect to said container to provide an annular space therebetween, a substantially ring-like flexible diaphragm arranged in said annular space and sealed adjacent to the outer perimeter thereof to said container and sealed adjacent to the inner perimeter thereof to said piston, wherein said diaphragm has an inner side in contact with the gas in said container and an outer side in contact with the atmosphere, whereby axial movement of said piston in said container effects the feed of the material in said diaphragm between the outer portion thereof disposed adjacent to said container and the inner portion thereof disposed adjacent to said piston and the consequent reversal of the circumferential strains in the material thus fed; said diaphragm being of composite sandwich construction including a gas-impervious inner layer of organic material, a resilient outer layer of organic material, an intermediate layer of textile fabric, a first layer of adhesive bonding said inner layer to said intermediate layer, and a second layer of adhesive bonding said outer layer to said intermediate layer, said inner layer being relatively thin and elastomeric and characterized by substantial stretchability in the circumferential direction of said diaphragm, said outer layer being relatively thick and elastomeric and characterized by both substantial stretchability and substantial compressibility in the circumferential direction of said diaphragm, said intermediate layer being relatively thin and elastic and characterized by great tensile strength in the radial direction between the inner and outer perimeters of said diaphragm and by both substantial stretchability and substantial compressibility in the circumferential direction of said diaphragm, each of said adhesive layers being relatively thin and characterized by substantial elasticity and flexibility after setting thereof, said composite diaphragm having a thickness of at least about $\frac{1}{4}$ ", the circumferential length of said composite diaphragm being both stretchable and compressible by about 0.6% to about 2% of the unstrained circumferential length thereof without inducing wrinkles in the material therein.

14. In a dry-seal pressure-type gasholder including a substantially cylindrical container and a substantially cylindrical piston axially movably arranged in said container, said piston being spaced radially inwardly with respect to said container to provide an annular space therebetween, a substantially ring-like flexible diaphragm arranged in said annular space and sealed adjacent to the outer perimeter thereof to said container and sealed adjacent to the inner perimeter thereof to said piston, wherein said diaphragm has an inner side in contact with the gas in said container and an outer side in contact with the atmosphere, whereby axial movement of said piston in said container effects the feed of the material in said diaphragm between the outer portion thereof disposed adjacent to said container and the inner portion thereof disposed adjacent to said piston and the consequent reversal of the circumferential strains in the material thus fed; said diaphragm being formed essentially of foamed elastomeric material that is characterized by resiliency and by both

circumferential stretchability and circumferential compressibility, said material also being resistant to atmospheric gases and to water vapor, said material of the inner side of said diaphragm also being both inert and highly impervious to the gas stored in said container, said diaphragm having a thickness in the general range $\frac{1}{4}$ " to $\frac{1}{2}$ ", the circumferential length of said diaphragm being both stretchable and compressible by about 0.6% to about 2% of the unstrained circumferential length thereof without inducing wrinkles in the material therein.
